DESIGN FOR A BOTTLE DISPENSING REFRIGERATOR OR THE LIKE

Boyce Malcolm Vise, Columbia, S. C., assignor of one-half to Samuel R. Coleman, Columbia,
S. C.

Application August 31, 1938, Serial No. 79,657

Term of patent 14 years

To all whom it may concern:

Be it known that I, Boyce Malcolm Vise, a citizen of the United States, residing at Columbia, in the county of Richland and State of South Carolina, have invented a new, original, and ornamental Design for a Bottle Dispensing Refrigerator or the like, of which the following is a specification, reference being had to the accompanying drawing, forming part thereof.

In the drawing:

I claim:

The ornamental design for a bottle dispensing refrigerator or the like, as shown.

BOYCE MALCOLM VISE.
